(57) **CLAIM**

We claim the ornamental design for the adjustable venturi aerator, as shown and described.

DESCRIPTION

FIG. 1 is a front perspective view of the adjustable venturi aerator, showing our new design;
FIG. 2 is a left side view thereof;
FIG. 3 is a right side view thereof;
FIG. 4 is a top plan view thereof;
FIG. 5 is a bottom plan view thereof;
FIG. 6 is a rear view thereof; and,
FIG. 7 is a front view thereof.
